ing textile material according to claim 1, wherein the compound of the said formula is 7-diethylamino-4-methylcoumarin.

3. The method of dry-cleaning and optically brightening textile material according to claim 1, wherein the compound of the said formula is 7-monomethylamino-4-methylcoumarin.

4. The method of dry-cleaning and optically brightening textile material according to claim 1, wherein the compound of the said formula is 7-dimethylamino-4-methylcoumarin.

5. The method of dry-cleaning and optically brightening textile material according to claim 1, wherein the

compound of the said formula is 7-monoethylamino-4-methylcoumarin.

6. The method of dry-cleaning and optically brightening textile material according to claim 1, wherein the compound of the said formula is 7-diethylamino-3,4-di-methylcoumarin.
